UNITED STATES PATENT OFFICE

143,935

DESIGN FOR AN EDUCATIONAL GAME DEVICE

Vee Howell Rhines, Dearborn, Mich.

Application August 6, 1945, Serial No. 121,261

Term of patent 7 years

(Cl. D34—5)

To all whom it may concern:

Be it known that I, Vee Howell Rhines, a citizen of the United States of America, residing at Dearborn, in the county of Wayne and State of Michigan, have invented a new, original, and ornamental Design for an Educational Game Device, of which the following is a specification, reference being had therein to the accompanying drawing, forming a part thereof, wherein:

Fig. 1 is a top plan view of an educational game device embodying my new design; and Fig. 2 is an edge elevational view thereof.

I claim:

The ornamental design for an educational game device, substantially as shown.

VEE HOWELL RHINES.
